BRUSH

Application filed April 2, 1932. Serial No. 602,686.

This invention relates, generally, to brushes; and the invention has reference, more particularly, to a novel brush of the type wherein the bristles are retained or held in place by twisted metal strands or wires, the said brush being adapted for general cleaning purposes and being especially suitable for use in cleaning automobiles and the like.

Brushes of the type having their bristles held in position by twisted metal strands or wires have not become very popular for automobile use or other uses requiring severe service because, among other reasons, of the difficulty of constructing these brushes so as to withstand rough handling and because of the difficulty of designing these brushes so that they will present a uniform and continuous bristle area of substantial size.

The principal object of the present invention is to provide a novel brush employing twisted bristle carrying strands, which strands are so constructed and arranged as to provide a strong and serviceable brush having a relatively large operative surface with the bristles thereof disposed for effective use over the entire surface of the brush.

Another object of the present invention lies in the provision of a novel brush of the above character having bristle carrying twisted strands arranged in a plurality of loops, one of which loops lies in the transverse plane of the brush, whereas another of these twisted strand loops lies in a plane extending substantially at right angles to the transverse plane of the brush, the said second loop lying within the confines of the first mentioned loop, the said loops being interconnected in a novel manner to provide a rigid construction of great durability.

Another object of the present invention is to provide a novel brush of the above character which is of simple construction and which is adapted to hold a sponge therewithin as for the purpose of retaining a sufficient quantity of water for desired application to the surfaces worked over by the brush.

Other objects of this invention, not at this time more particularly enumerated, will be

clearly understood from the following detailed description of the same.

The invention is clearly illustrated in the accompanying drawings, in which:

Fig. 1 is a view in front elevation of the novel brush of the present invention.

Fig. 2 is a view in side elevation of the structure shown in Fig. 1.

Fig. 3 is a schematic part sectional view taken substantially along line 3—3 of Fig. 2. 60

Fig. 4 is a part sectional view taken along line 4—4 of Fig. 1; and

Fig. 5 is a view similar to Fig. 1 but with parts broken away and illustrates a slightly modified form of construction. 65

Similar characters of reference are employed in all of the above described views to indicate corresponding parts.

Referring now to Figs. 1 to 4 of the drawings, the reference numeral 1 designates the novel brush of this invention as a whole. Brush 1 comprises a handle 2 having a recess or cavity 3 in its upper end for receiving and retaining the twisted bristle carrying strands of the brush. The brush 1 is formed with a transversely disposed loop 4 consisting of two strands or wires 5 and 6 twisted tightly upon one another with bristles 7 gripped therebetween. The bristles 7 are gripped substantially midway of their lengths by the tightly twisted strands 5 and 6 so that these bristles, as a result of the twist of the strands, are caused to extend outwardly in all directions from these twisted strands. The free ends of the loop 4 are pressed toward each other and project into the cavity 3 of the handle 2 and are firmly cemented therein as by a suitable cement or composition 8. The transversely disposed loop 4 is of substantially oval shape, thereby giving the brush an external contour in plan which is also substantially oval as is illustrated in Fig. 1. It is to be understood, however, that the loop 4 may have shapes other than oval, for instance, this loop may be square in shape. The loop 4 is preferably inclined rearwardly somewhat as especially shown in Fig. 2 so as to better present its working face for use.

At the upper center of the loop 4 or in the 100

bight of this loop there is held a ringlet 10 which is gripped between the two wires 5 and 6. A second ringlet 11 interlinks with the ringlet 10 and depends therefrom, as especially shown in Figs. 3 and 4. A loop 12 consisting of twisted bristle carrying strands or wires 13 and 14 is positioned within the confines of loop 4 and lies in a plane extending substantially at right angles to the plane of loop 4. The loop 12 is relatively narrow in comparison with its length and has the shape especially shown in Fig. 4. The lower free ends of this loop 12 are fixed in the recess 3 of handle 2. The two wires 13 and 14 at the upper end or bight of the loop 12 grip the ringlet 11 therebetween to thereby secure the upper end of this loop to this ringlet. The bristles 7' carried by the loop 12 project outwardly in all directions from the wires of this loop, thereby filling up the space within the center of loop 4 and giving the brush a substantial and solid central portion, so that the bristles of the brush continue across the entire face thereof, as especially shown in Fig. 1.

In order that the brush may hold a desired quantity of water in use, the same is illustrated in Figs. 1 and 4 as provided with a sponge or other absorbent body 15 that is positioned within the loop 12. Sponge 15 is held by a doubled over and twisted strand of wire 16, the upper end of which is looped through the ringlet 11 and the lower end of which is embedded in the cement 8 within cavity 3 of handle 2. With the sponge 15 included in the brush 1, the same will pick up and hold a desired quantity of water or washing liquid in use and will supply this liquid in regulated quantity to the surface being washed.

Owing to the practical continuity of the bristle surface extending completely across the face of the brush at both the front and back thereof, the brush is very effective in removing dirt. Also, the bristles of the two loops 4 and 12 mutually support one another and thereby prevent the undue flattening or distortion of these bristles in use. The simple expedient of using ringlets 10 and 11 serves to securely connect the two loops 4 and 12 together at their upper ends, whereas their lower ends are held firmly together within the cavity of handle 2. The mutual repulsion of those portions of the bristles 7 and 7', which lie within the interior of the brush, together with the natural tendency of the twisted metal strands of loops 4 and 12, owing to their resiliency, to expand these loops, serve to urge the loops outwardly into desired position, thereby greatly enhancing the rigidity of the brush. It will be noted that transverse loop 4 gives the brush great strength in a transverse direction while the loop 12 gives the brush its strength in a direction at right angles to loop 4. The pres-

ence of the sponge carrying wire 16 also enhances the strength of the brush.

It will be apparent that for some uses the sponge 15 will be unnecessary and therefore this sponge together with its twisted carrying strand 16 may be omitted on occasions, as illustrated in Fig. 5. The remaining parts of the structure of Fig. 5 are identical with those of the preceding figures. In the form of the invention illustrated in Figs. 1 to 4, wherein the sponge 15 is used, the wires 13 and 14 of the loop 12 are preferably made of smaller diameter than the wires of loop 3, and hence loop 12 will not be as stiff as loop 4, whereby loop 12 will be more or less flexible in use so that when pressure is applied to bristles 7', such pressure will deflect loop 12 sufficiently to effect the desired compression of sponge 15, so that liquid held by this sponge will be readily discharged therefrom and onto the surface being cleaned.

As many changes could be made in the above construction and many apparently widely different embodiments of this invention could be made without departing from the scope thereof, as defined by the following claims, it is intended that all matter contained in the above description or shown in the accompanying drawings shall be interpreted as illustrative and not in a limiting sense.

What is claimed is:

1. A brush comprising, a pair of closed loops, each of said loops consisting of strands tightly twisted together, bristles gripped between said strands, one of said loops lying in a plane extending transversely of said brush and the other of said loops lying within the confines of said first named loop and extending in a plane at right angles to said first named loop.

2. A brush comprising, a handle having a cavity in one end thereof, a closed loop of twisted strands disposed transversely of said brush, bristles gripped substantially midway of their lengths by said twisted strands and extending outwardly in all directions from said twisted strands, the free end portions of said twisted strands being brought together and rigidly mounted within the cavity of said handle, a second closed loop of twisted strands, additional bristles engaged between the strands of said second loop and extending outwardly in all directions therefrom, said second loop lying within the confines of said first named loop and positioned within a plane extending substantially at right angles to said first named loop.

3. A brush comprising, a handle having a cavity in one end thereof, a closed loop formed of twisted strands disposed transversely of said brush, bristles gripped substantially midway of their lengths by said twisted strands and extending outwardly in all directions from said twisted strands, the

free end portions of said twisted strands being brought together and rigidly mounted within the cavity of said handle, a second closed loop formed of twisted strands, additional bristles engaged between the strands of said second loop and extending outwardly in all directions therefrom, said second loop lying within the confines of said first named loop and positioned within a plane extending substantially at right angles to said first named loop, the free end portions of said second loop being brought together and rigidly mounted within the cavity of said handle, and fastening means interconnecting the bights of said first and second named loops.

4. A brush comprising, a handle having a cavity in one end thereof, a loop consisting of wire strands tightly twisted together and disposed transversely of said brush, bristles gripped substantially midway of their lengths by said twisted wire strands and extending outwardly in all directions therefrom, the free end portions of said twisted wire strands being rigidly mounted within the cavity of said handle, a second loop consisting of wire strands tightly twisted together, additional bristles engaged between the wire strands of said second loop and extending outwardly in all directions therefrom, said second loop lying within said first named loop and positioned within a plane extending substantially at right angles to the plane of said first named loop, links interconnecting the bights of said first and second named loops, and a sponge positioned within said second named loop.

5. A brush comprising, a handle having a cavity in one end thereof, a loop of twisted wire strands having their end portions fixed within the cavity of said handle, bristles engaged between the twisted wire strands of said loop and extending outwardly in all directions therefrom, a ringlet engaged between the wire strands of said loop at the bight thereof, a second ringlet interlinked with said first named ringlet, a second loop of twisted wire strands, the wire strands at the bight of said second loop engaging said second ringlet, the free end portions of said wire strands of said second loop being fixed in the cavity of said handle, a sponge contained within said second loop, and a doubled over and twisted wire strand gripping said sponge and having its looped end engaging said second named ringlet and its other end projecting fixedly into the cavity of said handle.

6. A brush comprising, a handle having a cavity in one end thereof, a transversely extending relatively wide loop of twisted wire strands having their end portions fixed within the cavity of said handle, bristles engaged between the twisted wire strands of said loop and extending outwardly in all directions therefrom, a ringlet engaged between the

wire strands of said loop at the bight thereof, a second ringlet interlinked with said first named ringlet, a second relatively narrow loop of twisted wire strands, said second loop being positioned within said first named loop and extending substantially at right angles to said first named loop, the wire strands at the bight of said second loop engaging said second ringlet, the free end portions of said wire strands of said second loop being fixed in the cavity of said handle, a sponge contained within said second loop, and a doubled over and twisted wire strand gripping said sponge and having its looped end engaging said second named ringlet and its other end projecting fixedly into the cavity of said handle.

In testimony that we claim the invention set forth above we have hereunto set our hands this 24th day of March, 1932.

FREDERICK EISENHUT.
CHARLES W. PENNINGTON.
